LIGHT SIGNAL

Wesley B. Wells, Wilkinsburg, Pa., assignor to
The Union Switch & Signal Company, Swiss-
vale, Pa., a corporation of Pennsylvania

Application June 10, 1936, Serial No. 84,501

3 Claims. (Cl. 177—329)

My invention relates to light signals, and particularly to light signals which are capable of selectively projecting a plurality of beams of light of different colors from a single light source. 5 More particularly, my present invention relates to operating mechanisms for such signals, and is an improvement on the operating mechanism described and claimed in Letters Patent of the United States No. 1,864,224, granted to me on 10 June 21, 1932.

I will describe one form of mechanism embodying my invention, and will then point out the novel features thereof in claims.

In the accompanying drawings, Figs. 1 and 2 are rear elevational and right-hand end views, respectively, of the operating mechanism embodying my invention. Fig. 3 is an isometric view of the field structure forming part of the operating mechanism shown in Figs. 1 and 2. 20 Fig. 4 is an isometric view of the rotor forming part of the operating mechanism shown in Figs. 1 and 2. Fig. 5 is a diagrammatic view showing a circuit for controlling the mechanism.

Similar reference characters refer to similar 25 parts in each of the several views.

Referring to the drawings, the operating mechanism is of the three-position motor relay type, and in the form here shown comprises a field structure A which is best illustrated in 30 Fig. 3, and a rotor B which is best illustrated in Fig. 4. Referring to Fig. 3, the field structure A comprises two spaced magnets M¹ and M², the like poles of which are connected by spaced backstraps 10 and 11, respectively. The magnets M¹ and M² may be of any suitable type, such for example, as the well-known electromagnets employing a magnetizable core carrying an energizing winding, but in order to decrease the cost of manufacture and to improve the efficiency of the 40 signal, I prefer to employ the construction illustrated in the drawings. As here shown, each magnet comprises two rectangular plates 1 and 2 of suitable magnetizable material, which plates are clamped between two pairs of vertically ex- 45 tending permanently magnetized rectangular bars 3 adjacent the upper and lower ends of the bars, respectively. The bars 3 of each pair are disposed in parallel spaced relation with one another, and are so arranged that their correspond- 50 ing ends are all of the same polarity. These bars are removably maintained in position by means of a clamping bolt 4 which extends horizontally through retaining clips 5, and between the bars 3 of each pair of bars at a point approximately 55 midway between their ends. The clips 5 are

provided with ears 5^a at each end, which ears overlap the opposite sides of the two bars of each pair for holding the bars in the proper spaced relation. To prevent the bolts 4 from turning while the associated nut 4^a is being 5 tightened or loosened, an auxiliary clip 6 is interposed between the head of the bolt and the associated clip 5. This auxiliary clip extends transversely of the associated clip 5, and is provided at its inner side with a horizontal channel 6^b 10 which receives the associated clip 5, and on its outer side with spaced parallel ribs 6^a which engage the opposite sides of the rectangular head of the bolt 4. A flat locking plate 7 (see Fig. 2) is interposed between each nut 4^a and the associated clip 5. This locking plate is made of deformable material, and after the nut is tightened, one end of this plate is bent into engagement with the edge of the associated clip, and the other end is bent into engagement with 20 the nut, thus preventing the nut from becoming loosened. A spacing block 8 of brass or other suitable non-magnetizable material is interposed between the plates 1 and 2 of each magnet, and the spacing block, plates, and backstraps are all 25 securely fastened together by means which will be described hereinafter. Each block 8 is provided with a horizontal slot 9 through which the clamping bolt 4 passes with some clearance, and which is open at its outer end to permit the bolt 30 to be inserted or removed from the slot by sliding it outwardly at right angles to the axis of the block 8. It will be noted that the width of the spacing block is less than the width of the plates 1 and 2, thus providing clearance 35 between the block and the bars 3. Clearance is also provided between the ends of the bars and the backstraps 10 and 12. By means of this construction, the four bars of either magnet may be removed from the field structure for inspection or replacement merely by loosening the associated nut 4^a, and sliding the bolt, clips, and bars outwardly in the direction of the axes of the backstraps (see Figs. 1 and 2). Furthermore, with this construction, the remainder of the 40 operating mechanism may be assembled before the bars are added to the field structure. This is a distinct advantage, because, if the magnetizable bars were assembled to the field structure before the remainder of the operating mechanism 45 of the signal was assembled, then while the remainder of the operating mechanism was being assembled, iron and steel filings might be attracted to the bars, which is undesirable. By assembling the mechanism completely without 50 55

the bars, the operating mechanism can be cleaned either with a vacuum or a blast of air, and the bars can be freed of all filings and assembled as a last operation.

- 5 It should be pointed out that the magnetic contact between the bars 3 and the backstraps 10 and 11 is made through the medium of the plates 1 and 2, and not at the ends of the bars, so that no machining of the bars is necessary
- 10 other than cutting them to the desired length, which operation need not be done with great accuracy. It will be seen, therefore, that magnets constructed in the manner shown are very economical to manufacture. It should also be
- 15 pointed out that, while I have shown each magnet as comprising four permanently magnetized bars, this number is not essential to my invention, but may be varied in accordance with the field strength which it is desired to attain.
- 20 Associated with the backstrap 10 are two pole pieces 12 and 13, and associated with the backstrap 11 are two pole pieces 14 and 15. As here shown, these pole pieces are L-shaped, being formed with horizontally extending legs 12^a, 13^a,
- 25 14^a, and 15^a, respectively, and with vertically extending legs 12^b, 13^b, 14^b, and 15^b, respectively. The horizontal leg of each pole piece is fastened to the associated backstrap by means of screws 16 and 17. Each screw 16 extends with clearance
- 30 through a suitable hole in the pole piece and is screwed into a threaded hole in the associated backstrap. Each screw 17 extends through a suitable clearance hole in the pole piece, into and through a threaded hole in the associated backstrap, and through a clearance hole in the adjacent plate 1 or 2. It then passes into a clearance hole in the adjacent block 8. It thus prevents plates 1 and 2 from turning about an associated tap bolt 19 described hereinafter. It will be ap-
- 35 parent, therefore, that the screws 17 serve both as a means for fastening the pole pieces to the backstraps, and as a part of the means referred to hereinbefore for fastening the backstraps 10 and 11, plates 1 and 2, and spacing block 8 together. The pole pieces 12 and 13 are spaced apart, and are disposed with their vertical legs extending downwardly on opposite sides of the backstrap 10, and the pole pieces 14 and 15 are similarly spaced apart and are disposed with their
- 40 vertical legs extending upwardly on opposite sides of the backstrap 11 directly opposite the downwardly extending legs of the pole pieces 12 and 13. For reasons which will appear hereinafter, the vertical legs 12^b and 13^b of the pole pieces 12 and 13 are made sufficiently long so that they extend downwardly to a point opposite the lower backstrap 11, while the legs 14^b and 15^b of the pole pieces 14 and 15 are made relatively short. It will be apparent, therefore, that the field structure embraces two pairs of pole pieces, the one pair of which 12 and 15 are located on one side of, and adjacent the opposite ends of, the backstraps 10 and 11. It will also be apparent that the pole pieces 12 and 13 will be of one polarity, while the pole pieces 14 and 15 will be of the opposite polarity. For example, if the bars 3 are disposed with their
- 45 north magnetic poles located at the upper ends of the bars, the pole pieces 12 and 13 will be north poles, while the pole pieces 14 and 15 will be south poles. The outer faces of the pole pieces of each pair are disposed in the same vertical
- 50 plane.

The tap bolts 19 referred to hereinbefore each pass through a clearance hole in the associated backstrap, into and through a clearance hole in the associated plates 1 and 2, and is screwed at its lower end into the spacing block 8. It will be noted that the tap bolts 19 serve as part of the means referred to previously for clamping the backstraps 10 and 11, plates 1 and 2, and spacing blocks 8 together.

Attached to the lower backstrap 11 by means of screws 20 is a non-magnetizable bracket 21. This bracket is substantially U-shaped, and the upwardly extending arms 21^a and 21^b thereof are provided in their upper ends with aligned knife-edge bearings 22 and 23, respectively, in which the rotor B referred to hereinbefore is journaled, as best seen in Fig. 2. The bearings 22 and 23 may be of any suitable construction but, as here shown, these bearings are similar in all respects to those described and claimed in my copending application for Letters Patent of the United States Serial No. 748,506, filed on October 16, 1934, for Bearings and method of manufacturing the same.

Referring now also to Fig. 4, the rotor B, in the form here shown, comprises a core 25 of suitable magnetizable material, such as silicon steel, provided adjacent its ends with shoulders 25^a and 25^b (see Fig. 2) against which downwardly extending armatures 26 and 27 are clamped by means of nuts 28 and 29, respectively. End pins 33 of suitable material, such as hardened steel, are inserted in the ends of the core 25, and these pins are mounted to rotate in the knife-edge bearings previously described. The armature 26 is adapted to cooperate with the pole pieces 12 and 15, and is spaced from the outer or pole faces of the vertical legs 12^b and 15^b of these pole pieces by vertical air gaps; as will be seen from an inspection of Fig. 2. The armature 27 is likewise adapted to cooperate with the pole pieces 13 and 14, and is spaced from the outer or pole faces of the vertical legs 13^b and 14^b of these pole pieces by vertical air gaps. The armatures 26 and 27 are of magnetizable material, and are provided with ears 26^a, 26^b, 27^a, and 27^b which taper from the center of the armature as shown, the reasons for tapering these ears being explained hereinafter.

Clamped between the nut 28 and the armature 26 is a triangular bracket 34, and attached to the outer side of this bracket on opposite sides of the core 25 of the rotor B, as best seen in Figs. 1 and 2, are two studs 30 and 31 which carry rollers 30^a and 31^a, respectively. These rollers cooperate with suitable means (not shown) for biasing the rotor to a middle or normal position in which the longer axes of the armatures 26 and 27 are substantially vertical, and also with suitable contact mechanism (not shown) which is selectively operated in response to rotation of the armature. These biasing means and contact mechanism form no part of my present invention and may, for example, be similar to that described in my prior United States Patent No. 1,864,224 referred to hereinbefore. It will be obvious that the armatures 26 and 27 due to the manner in which they are disposed also serve to bias the rotor to its normal position.

A spectacle arm 32 is rigidly attached at its lower end to the armature 27 of the rotor B in such manner that, when the rotor occupies its normal position, the spectacle arm will be vertical, and this spectacle arm is provided at its upper end with three filters G, R, and Y which cooperate with the optical system of the signal

in which the operating mechanism is used in a manner which is fully described in my above referred to patent, to cause the signal to indicate proceed, stop, or caution according as the rotor is 5 swung to a left-hand extreme position, occupies its intermediate position, or is swung to a right-hand extreme position, as viewed in Fig. 1. The parts are so proportioned that the spectacle arm is substantially counterbalanced by the armatures 26 and 27, whereby a balanced rotor is 10 obtained without the necessity of additional counterbalancing means.

A slow-acting coil 35 surrounds the core 25 of the rotor R, and is held in place by two 15 brackets 36 which are secured intermediate their ends to the backstraps 10 and 11, respectively, and which fit into suitable slots formed in the insulating end plates of the coil. The construction of the coil 35 and the method of securing 20 it to the backstraps form no part of my present invention, and may, for example, be similar to that shown in my prior Patent No. 1,864,224. The coil 35 is intended to be reversibly supplied 25 with current, and for this purpose I have shown 25 in Fig. 5, a battery C which is connected with this coil over a pole changer P. As illustrated in the drawings, the pole changer is manually operated, but in actual practice this pole changer will normally be replaced by pole-changing contacts 30 of a relay, or by contacts operated by another mechanism similar to that shown herein.

Assuming for purposes of explanation that the magnets M¹ and M² are so disposed that the pole pieces 12 and 13 become north poles, and the 35 pole pieces 14 and 15 become south poles, the operation of the operating mechanism as a whole is as follows: When pole changer P occupies its middle position in which no current is supplied to the coil 35, as shown in the drawings, the only 40 flux which threads the armatures 26 and 27 is the flux from the associated pole pieces 12, 15, 13, and 14, and the armatures are so shaped and the parts are so proportioned that this flux will exert no appreciable torque on the rotor. Under 45 these conditions, the rotor is held, due to the biasing means referred to hereinbefore, in its intermediate position in which the signal displays a stop indication.

If, now, pole changer P is thrown in such a 50 direction that winding 35 is supplied with current of normal polarity, armature 26 becomes a north pole and armature 27 becomes a south pole. Under these conditions, the pole piece 12, being a north pole, repels the armature 26, and 55 the pole piece 15, being a south pole, attracts the armature 26, while the pole piece 13, being a north pole, attracts the armature 27, and the pole piece 14, being a south pole, repels the armature 27. A torque is therefore exerted on rotor R 60 which torque rotates the rotor in a counter-clockwise direction, as viewed in Fig. 1, to its left-hand extreme position in which it is stopped by means of the mechanism which is actuated by the roller 31^a. When the rotor occupies its left-hand extreme position, the signal displays a proceed indication as explained hereinbefore.

If pole changer P is thrown in such a direction that coil 35 is supplied with current of reverse polarity, armature 26 then becomes a south 65 pole and armature 27 becomes a north pole. Under these conditions, armature 26 is attracted by pole piece 12 and repelled by pole piece 15, while armature 27 is repelled by pole piece 13 and attracted by pole piece 14, so that a torque is 70 exerted on rotor R which rotates it in a clock- 75

wise direction, as viewed in Fig. 1, to its right-hand extreme position in which it is stopped by means of the mechanism which is actuated by the roller 30^a. When the rotor occupies its right-hand extreme position, the signal displays a 5 caution indication, as explained hereinbefore.

It should be particularly pointed out that with the armatures 26 and 27 mounted in depending vertical positions in the manner described, the rotor may be made considerably lighter in weight 10 than has heretofore been possible. This reduction in weight of the rotor is desirable for two reasons. In the first place, it reduces the weight on the knife-edge bearings, thus increasing their life. In the second place, it reduces the 15 momentum attained by the rotor when travelling from one extreme position to the other, and hence decreases the tendency of the rotor to rebound when it reaches either extreme position.

It should also be particularly pointed out that 20 with the armatures 26 and 27 mounted in depending vertical positions in the manner described, the magnetic pull which is exerted on these armatures when the coil 35 is energized is a downward pull toward one side or the other, 25 depending upon the direction of energization of the coil, thus insuring that the rotor will not be lifted off of its bearings.

It should further be pointed out that since the 30 armatures 26 and 27 are formed with tapered 30 ears, as previously described, a greater torque is exerted on the rotor near the end of its stroke in either direction than at the beginning, this added torque being desirable for compressing the front contacts of the contact mechanism. 35

Although I have herein shown and described only one form of signal mechanism embodying my invention, it is understood that various changes and modifications may be made therein within the scope of the appended claims without 40 departing from the spirit and scope of my invention.

Having thus described my invention, what I 45 claim is:

1. An electroresponsive device comprising a 45 field structure consisting of two magnets having their like poles connected by vertically spaced horizontally extending backstraps, first and second pole pieces secured to the upper backstrap adjacent the opposite ends thereof and third and fourth pole pieces secured to the lower backstrap below said first and second pole pieces, respectively, said first pole piece being provided with a depending vertical portion which is disposed on the same side of said field structure, and in the 50 same vertical plane, as an upwardly extending vertical portion which is provided on said fourth pole piece, and said second pole piece being provided with a depending vertical portion which is disposed on the opposite side of said field structure from the depending portion of said first pole piece and in the same vertical plane as an 55 upwardly extending vertical portion which is provided on said third pole piece, a rotor comprising two depending armatures connected by a magnetizable core and one separated from the vertical portion of said first and fourth pole pieces by vertical air gaps and the other separated from the vertical portions of said second and third pole pieces by vertical air gaps, and means for 60 reversibly supplying flux to said rotor.

2. An electroresponsive device comprising two 65 magnets each consisting of a plurality of permanently magnetized bars clamped against two magnetizable plates located adjacent the upper 70 75

and lower ends of the bars respectively, said bars being disposed in such manner that their corresponding ends are all of the same polarity, two backstraps one fastened to the corresponding plates of both magnets at each end of the magnets for connecting the like poles of the magnets together, two pairs of pole pieces attached to said backstraps in such manner that the pole pieces of each pair are of opposite polarity and are laterally spaced from each other and are provided with pole faces which are located in the same vertical plane, the corresponding pole pieces of the two pairs of pole pieces being of the same polarity, a rotor comprising two depending armatures connected by a magnetizable core and one separated adjacent its lower end from the pole pieces of each pair by vertical air gaps, and a fixed coil surrounding said core for reversibly supplying flux to said rotor.

3. A light signal comprising an electroresponsive device including a rotor having two depending armatures connected by a magnetizable core, said rotor being rotatable between two extreme positions, an upwardly extending spectacle arm secured to the rotor, said spectacle arm and said armatures being so proportioned that said spectacle arm is substantially counterbalanced by said

armatures, means for reversibly supplying flux to said rotor, a first pair of constantly magnetized pole pieces of opposite polarity disposed on opposite sides of the vertical plane passing through the axis of said rotor and having pole faces disposed in the same vertical plane and separated from the one armature adjacent its lower end by vertical air gaps in such manner that the one pole piece of said first pair will attract and the other will repel said armature or vice versa according as said rotor is supplied with flux of one polarity or the other, and a second pair of constantly magnetized pole pieces of opposite polarity disposed on opposite sides of the vertical plane passing through the axis of said rotor and having pole faces disposed in the same vertical plane and separated from the other armature adjacent its lower end by vertical air gaps in such manner that the one pole piece of said second pair will attract and the other pole piece will repel said other armature or vice versa according as said rotor is supplied with flux of one polarity or the other, said two pairs of pole pieces being so arranged that the torques exerted on the rotor by both armatures at any instant will be additive.

WESLEY B. WELLS.
